FIGURE 1 is a perspective view of the combined grave ledger and marker showing my new design;

FIGURE 2 is a side elevational view thereof;

FIGURE 3 is an end elevational view thereof looking from the lower end of FIGURE 1; and

FIGURE 4 is an end elevational view thereof looking from the opposite end of that shown in FIGURE 3.

The dominant features of my design reside in those portions shown in full lines in the drawings.

I claim:

The ornamental design for a combined grave ledger and marker, substantially as shown and described.
